PLASTERER'S IMPLEMENT

Charles J. Jacobsen and Hugo Battistone, Washington, D. C.; said Jacobsen assignor to said Battistone

Application February 7, 1939, Serial No. 255,158

9 Claims. (Cl. 306—38)

Our invention relates to plasterers' implements and more particularly to straight edges for use by plasterers in finishing the interior plaster work in buildings and includes an implement designed for finishing the corner portions as well as the plane surfaces of walls and ceilings; and the nature and objects of the invention will be readily recognized and understood by those skilled in the arts to which it relates in the light of the following explanation and detailed description of the accompanying drawing illustrating what we at present believe to be the preferred embodiment or mechanical expressions of our invention from among various other forms, arrangements, combinations and constructions, of which the invention is capable within the spirit and scope thereof.

The usual type of plasterer's implement which is now in use for finishing the interior surfaces of walls and ceilings consists of a handle portion and a straight edge blade which may be either of the square edge type or of the feather edge type or the like. The straight edge blade or surface is usually made of wood, and, therefore, becomes warped and otherwise damaged in use so as to be useless to perform the work for which it is designed. In plasterers' implements of this type in which the blade and handle are constructed in one piece, it is, therefore, necessary when the blade loses its utility to discard the entire implement, even though the handle may be in perfect condition. Such procedure is costly and constitutes a needless waste. In such tools that are constructed with a removable blade, difficulty has been encountered in so mounting and attaching a new blade to the handle as to present a sufficiently true and straight edge which is essential for the type of work for which the implement is designed. Ease of assembly and quick automatic truing of the new blade are desirable characteristics of such an implement and by our arrangement such features have been attained.

It is therefore an object of this invention to provide a plasterer's implement which overcomes this expensive defect which is now inherent in such tools.

It is a further object of this invention to provide a plasterer's implement so designed that the handle may be used indefinitely and new blades may be attached thereto to replace blades which have been damaged.

A further characteristic of this invention is to provide means on the handle for easily receiving a new blade thereon, and fastening the

blade thereto in a manner to insure the true positioning of the blade.

A still further object of this invention is to provide a plasterer's implement which is accurate in its positioning of new blades thereon and yet economical in its original construction and in the upkeep thereof.

It is also a characteristic of this invention to provide a plasterer's implement to which a blade may be quickly attached and automatically trued thereon with a minimum amount of attention from the user, and one from which a blade may be removed with great facility.

A still further object of this invention is to provide a plasterer's tool designed for the removal and attachment of blades to the handle thereof, there being provided a coarse and a fine adjustment for truing and securing the blade thereon.

With the foregoing general objects, features, and results in view, as well as certain others which will be apparent from the following explanation, the invention consists in certain novel features in design, construction, mounting and combination of elements, as will be more fully and particularly referred to and specified hereinafter.

Referring to the accompanying drawing:

Fig. 1 is a perspective view of the assembled device.

Fig. 2 is a section taken on the line 2—2 of Fig. 1, showing the position of the elements before the blade has been tightened on the handle.

Fig. 3 is a section similar to that shown in Fig. 2 with parts broken away, and shows the position of the elements after the blade has been tightened on the handle.

Fig. 4 is a section similar to that shown in Fig. 2, with a square blade instead of a feather edge blade applied to the handle.

Referring to the drawing, the long relatively narrow handle 1 of the plasterer's implement is preferably made of wood and is provided on opposite sides thereof with elongated concavities 3 which serve as fingerholds for the operator or operators of the device, and is further formed with the lower corners cut off diagonally to facilitate the operation of the straight edge in the angles between walls, ceilings, and the like. It is to be understood that our plasterer's implement may be made in varying lengths as desired, and may be operated at one time by one or more men depending on the length of the implement.

The upper longitudinal edge of the handle is

formed concave in cross section as designated by the numeral 5, and a channel member 7 of substantially U-shape having upwardly converging sides 9 is secured to the upper longitudinal concave edge of the handle, and is so disposed thereon that the base of the channel member rests on the edges of the concavity and extends thereacross. The channel 7 is a metallic member formed of brass, aluminum or the like metal 10 of a gage to insure a certain degree of resiliency. For the purposes of our invention as will be described in detail hereinafter, it is necessary that the channel be made of a metal having sufficient resiliency so that under certain conditions it may be so distorted as to buckle or flex in its base portion to extend or bend into the concavity 5 of the handle. At the time of distortion of the base portion of the channel member 7 it is to be noted and will be made 15 clear later in the description of this invention that the upwardly converging sides 9 of the channel member will be bent to extend inwardly to a greater degree than when the channel member is in normal position as shown in Fig. 2 of the 20 drawing.

The base or bottom portion of the channel member 7 which extends across the concave longitudinal upper edge of the handle is drilled to provide a plurality of spaced holes therein for 25 receiving screws 11 which are adapted to screw into the wooden handle 1 for securely fastening the channel member to the top edge of the handle in the proper and desired true position. While we have shown only two of such channel 30 securing screws it is apparent, of course, that any desired number may be used to properly and firmly attach the channel member to the handle. The channel member 7 is secured to the handle, by means of the screws which have just been 35 described, in the proper and desired position to accurately dispose a blade therein when the device is being assembled for use.

The straight edge or blade which is preferably 40 formed of a wood, such as white pine or the like, is constructed in the form of a feather edge blade 13 or a square edge blade 14 as disclosed particularly in Fig. 4, or in any shape or form found useful in performing a particular type of work. The blade 13 whether it be of the feather edge type, or the square edge type or the like, is 45 adapted to be removably received in the channel member 7 in proper and true position therein, and each blade is provided with a cut-out section 15 along the lower portion of the opposing sides thereof. The cut-out portion is made of a size to relatively loosely and slidably receive 50 therein the upstanding converging sides 9 of the metallic channel member. The blades 13 are produced in varying lengths, a particular blade being selected for use which is of the same 55 length as the handle with which it is to be associated, and when a blade is in position in the channel the upstanding sides 9 fit into the cut-out portions 15 in such manner as to present flat substantially unbroken surfaces to the sides of 60 the blade.

As hereinbefore pointed out the channel member 7 is secured in proper and accurate position on the handle by the screws 11, and as the blade is loosely received in the channel it is necessary to tightly secure the blade in true position within the channel member so as to be held therein against removal upon being submitted to stresses and strains encountered in actual work.

75 The means by which we tightly secure the

blade on the handle also automatically trues the blade with respect thereto to provide a highly accurate and true plasterer's straight edge. To accomplish this, we provide the base of the channel member 7 with holes 19 formed centrally 5 therein and longitudinally spaced therealong. The handle 1 is provided with complementary holes 21 therein extending through the handle from the top concave edge to the bottom thereof. It is to be understood that a hole 21 is provided 10 for each hole 19 in the channel member, and as these are aligned it is apparent that an opening extends from above the base of the channel member to the bottom edge of the handle 1. Placed through each of the holes 19 in the channel 15 member from above and extending downwardly into the handle hole 21 is a hollow interiorly threaded bolt 23 having a flaring head 25 which rests upon the top surface of the base of the channel member. While we have shown only 20 two of such bolts it is apparent that any number may be used which may be found advantageous. The base of the blade 13 is provided with a longitudinally extending centrally disposed dovetailed groove 27 for longitudinally slidably receiving the flaring head 25 of each bolt 23. When the blade is in position entirely within the channel member it is tightly secured and trued on the handle by means of screw 29, the head 31 of which is disposed in a socket formed in the 30 lower edge of the handle 1 and bears against a metallic disk 33. A screw 29 is provided for each bolt 23 which is being used in the device, and the shank of each screw extends upwardly and threads into the hollow bolt 23. Therefore, 35 by screwing each one of the screws 29 into the hollow bolt 23 the blade 13 will be tightly secured in true position within the channel member as disclosed in Fig. 3 of the drawing particularly, and conversely by unscrewing the screw 29 the 40 blade will be loosely held in the channel member 7 as disclosed particularly in Fig. 2 of the drawing.

Assuming that the blade 13 in Fig. 2 of the drawing is damaged and it is desired to remove the same from the handle for attachment of a new blade thereto. The blade in this particular figure of the drawing is loosely or longitudinally slidably disposed within the metallic channel member because the screw is not screwed up 45 tightly into the bolt, hence it is merely necessary to slide the blade out of the channel member from either end thereof, and upon complete removal of the blade a new blade is slid into either 50 end of the channel member. As a new blade is slid into the channel member the flaring heads 55 25 are received into the groove 27 formed in the base of the blade and the sides 9 of the channel member are received in the portions 15 on the blade. With the blade disposed within the resilient channel member and before the screw is tightened it is held on the handle in relatively accurate or coarse adjustment, however, before using the implement in actual work the user must tightly secure the blade on the handle 60 which, as will be explained, automatically trues the blade on the handle. With the blade slidably disposed in the channel member as disclosed, particularly in Fig. 2 of the drawing, the screw 29 is screwed into the hollow bolt 23 which draws 65 the blade downwardly into the resilient channel member through the action of the flaring head 25 of the bolt within the groove 27. Such tightening of the screw within the bolt also distorts 70 the channel member. The lower surfaces of the 75

flaring head engage the top surface of the base of the channel member to bend or distort it downwardly to flex into the concavity 5 as disclosed, particularly in Fig. 3 of the drawing. The arrangement of a concave surface upon which the resilient channel member is disposed insures distortion thereof upon the application of the proper pressure, and such distortion results in tightly securing and fastening the blade in rigid 10 and true position. When the base of the channel member flexes into the concavity, the upstanding sides 9 thereof will be forced inwardly to bite into the opposite sides of the blade to accurately and truly position the blade, thereby 15 locking it against removal from the handle. This distortion of the channel member which causes the sides 9 to bite into and securely hold the blade in position insures an automatic truing of the blade due to the fact that the channel member itself is held in proper position on the handle by means of the screws 11, and as the tension on each of the upstanding sides 9 will be equal 20 due to the medial position of head 25 of the bolt with respect to member 7, the blade will automatically be disposed in true position. A fine 25 adjustment is thus automatically achieved when the blade is securely fastened within the channel member and the implement is ready for actual use.

30 The square edge type of blade as disclosed by numeral 14 in Fig. 4 of the drawing and any other useful form of blade is constructed with the same elements for cooperation with the handle securing means as is the blade 13 which has 35 been described, and hence it is not believed that a detailed description of this type of blade is necessary.

What I claim is:

1. A plasterer's implement including a handle 40 having a concave edge and a resilient member mounted on said concave edge and distortable to flex thereinto, a blade adapted to be received and locked in said resilient member, an element associated with said blade and depending therefrom through said resilient member into said handle, and means within said handle operatively connected with said element for exerting pressure thereon to cause distortion of said resilient member.

50 2. A plasterer's straight edge and the like, comprising a longitudinally elongated blade; and a longitudinally elongated handle-forming carrier, said blade and said carrier being removably secured together in normal parallel longitudinal 55 relationship with the blade and carrier in a common longitudinal plane, adjoining longitudinal parallel portions of the carrier and blade being of substantially the same transverse thickness, said blade substantially throughout its length having a longitudinal base portion, said carrier at a straight longitudinal edge being provided with a longitudinal channel secured thereto and complementary to said blade base for longitudinal endwise sliding of the blade into and from the channel, said channel and blade base being so formed as to interlock against relative lateral transverse separation, and means for locking the blade against and for releasing the same for endwise sliding movement from the channel.

60 70 3. A plasterer's straight edge, comprising a removable longitudinally elongated straight edge blade formed with a longitudinal base having a longitudinal portion of reduced transverse width, said blade also formed with a longitudinal substantially dovetailed groove opening through the

bottom face of the blade base, in combination with a handle-forming carrier, said carrier having a straight flexible wall longitudinal channel secured thereto, said channel being complementary to the base of said blade for endwise longitudinal application of the blade thereto and its removal therefrom, and clamping means operatively associated with said channel to flex the same for clamping the blade base between the channel side walls, said clamping means including at least a projecting portion normally located in said blade groove. 5

4. A plasterer's straight edge, comprising a longitudinally elongated straight edge blade of uniform cross sectional dimensions substantially throughout its full length, and a longitudinally elongated handle-forming carrier normally secured to and arranged longitudinally of and parallel with said blade; said blade throughout its length having a longitudinal base portion and a longitudinal groove extending substantially throughout the length of said base portion with a relatively narrow longitudinal side slot opening through the floor of said base between the longitudinal side faces thereof, a channel secured to said carrier and arranged longitudinally along a longitudinal edge thereof and having upstanding side walls or flanges, said channel in cross section being complementary to the blade base in cross section to receive and hold the same, and clamping means mounted to said carrier and comprising a head arranged in said groove of the blade base, and enlarged above said side slot, for clamping the blade down in the channel. 10 15 20 25

5. A plasterer's straight edge, comprising a longitudinally elongated blade having a longitudinal base portion, and a handle-forming carrier provided with an edge having a substantially centrally depressed longitudinal floor and marginal parallel longitudinal elevations, a resilient channel secured to said carrier and arranged longitudinally of said carrier straight edge with the flanges of the channel upstanding and the channel floor seated on said longitudinal elevations, the base of said blade being complementary to said channel, and clamping means operatively associated with the floor of said channel to flex the same toward said depressed floor of said carrier edge to thereby press the side walls of the channel into clamping engagement with the side 30 35 40 45 50 walls of the blade base. 55

6. A plasterer's implement including a longitudinally elongated handle-forming carrier provided along a longitudinal edge thereof with a longitudinal blade-clamping channel of substantially dovetail formation in end elevation, said channel including opposite upstanding longitudinal marginal flanges capable of transverse movements, a longitudinally elongated removable straight edge blade having a longitudinal base portion of substantially dovetail formation complementary to said channel, said blade base having a longitudinal groove opening through at least one end thereof and longitudinally opening laterally through the bottom of said base, said groove being of substantially dovetail formation, and clamping means associated with said carrier for clamping said base down in the channel and for pressing said flanges laterally inwardly to clamp said base, said means including at least one head in said base groove and operatively associated with said flanges, and manually actuated screw-threaded connections. 60 65 70

7. A handle-forming carrier for the removable longitudinally elongated blade of a plasterer's 75

- straight edge, said carrier provided with a longitudinally elongated resilient channel secured thereto longitudinally of a longitudinal edge, with its opposite marginal clamping flanges upstanding, said carrier provided with manually actuated means for flexing said channel to force said flanges laterally substantially toward each other to blade clamping positions.
8. An applicable and removable blade for the handle-forming carrier of a plasterer's straight edge, said blade being longitudinally elongated and of substantially uniform cross sectional dimensions throughout its length, said blade having a longitudinal base portion of substantially dovetail formation in end elevation, said base portion having a substantially dovetail longitudinal
- 5
- 10
- 15

groove opening through at least one end of the base and longitudinally opening laterally through the bottom longitudinal edge of said base.

9. A plasterer's implement comprising a removable straight edge blade, and a handle, said handle having a resilient longitudinal channel secured thereto with its opposite marginal clamping flanges approximately extending inwardly and upwardly to receive between them the base portion of the blade seated in the channel, 10 and manually actuated means carried by the handle for flexing said channel to draw said flanges into clamping relation.

HUGO BATTISTONE.
CHARLES J. JACOBSEN.
